HAND SEWING INSTRUMENT

David A. Merson, Great Neck, and Irving J. Moritt, Brooklyn, N. Y.; said Merson assignor to said Moritt

Application January 16, 1945, Serial No. 573,030

10 Claims. (Cl. 112—169)

1

The invention is a hand sewing machine of the kind which is held in the hand when being used and operated by squeezing and releasing a pair of plier-type handgrips, the purpose being to improve the practicability of instruments of this kind as well as to reduce their manufacturing cost so that their special utility can be made more generally available.

The accompanying drawing exemplifies the invention in the form at present preferred, Fig. 1 being a perspective; Fig. 2, a side elevation with parts in section and in the upstroke position; Fig. 3, a similar view in the downstroke position; Fig. 4, an end view with the looper case in section; Fig. 5, a top plan of the looper case; Fig. 6, a section on line 6—6 of Fig. 4; Fig. 7 is a vertical section on line 7—7 of Fig. 4 through the table member; Figs. 8 and 9 are plans representing successive positions of the oscillating shuttle; Fig. 10 is a front view in enlarged scale of the stitch adjustment, and Fig. 11 is a side view of Fig. 10 partly in section.

The two handgrip levers, 1 and 2, cross each other and are fulcrummed together at their crossing point 3. The needle bar 4 and the work-table base 5 are each pivotally connected to each handgrip by two pivot pins, namely the pins 6 and 7 in front of the fulcrum and the pivot pins 8 and 9 in rear of it, and the latter pins work in slots formed respectively in the needle bar and table members as indicated. All four pivot pins are equally distant from the fulcrum 3 and the slots which embrace the rear pivots 8 and 9 are parallel to each other so that the operation of the handgrips causes the bar and table members to approach and recede from each other with a straight line motion, being always parallel to each other. Also, they approach with a powerful action due to the compounding of the leverage.

The two handgrips are hollow sheet-metal stampings shaped to fit the hand comfortably and both are shown as housing springs 10, appropriately fastened to them so as to pull on the ends of the needle bar and table base, respectively, thus urging the parts to their open or upstroke position.

The needle bar 4 carries the needle 11 at its extreme end, held thereon in an appropriate socket 12, and fixed therein by a thumb screw 13. This is an ordinary straight sewing machine needle, and when secured in the socket, is exactly perpendicular to the needle bar, which is to say, parallel to the line of approach of this bar to the work-table. The needle bar also carries the work

feed-actuating cam 14 and the take-up 15, as well as the looper-actuating stud 16, presently described.

Thread is supplied to the needle from a spool, which is an ordinary spool, housed in a spool chamber inside of the handgrip 1, and mounted to turn therein on a spindle 17 carried on the spool-holder cap 18, which is screwed on or otherwise removably attached to the end of the handgrip so as to close the spool chamber. In threading up, the thread drawn from the spool is first slipped sidewise through the slot 19 (Fig. 1) into the handgrip outlet hole 20, and is thence led under the adjustable tension disc 21 through a fixed eye 22, through the eye in the take-up 15 and the second fixed eye 23, and thence to the needle. As will be apparent, manipulating the screw on the tension device 21 varies the spring pressure on the disc 21 so as to adapt the tension of the thread to the particular sewing conditions. Where the thread overlies the handgrip it is covered by a rigid shield 24 so that the pressure of the hand will not affect the tension.

The take-up 15 is mounted to rock and reciprocate in an aperture in the needle bar, being held therein by a slot and pin mounting 25, and is actuated in the present case by an extension 26 from the handgrip 2, integral therewith. It descends thereby releasing the tension on the thread when the handgrips close (Fig. 3), and rises to restore the tension when they open, at the same time drawing more thread from the spool wherewith to feed thread for the next stitch, its action being in all respects similar to that of customary take-ups.

The work-table 27 affords a smooth flat surface to support the fabric being sewed and is shown in the drawing as a flat plate, rigidly fixed in a slot in the table base 5, although it could be integral therewith if desired. It is perforated to receive the point of the needle and allow it to enter into the looper chamber below.

This looper chamber is a round-bottomed cup-shaped case 28, made as shallow as circumstances permit, and is pivoted on the base 5 on a screw 29, which can be the same screw that locks the work-table plate in its slot as shown. It is held in its working position by a ball-detent 30 and by swinging it on its pivot (the needle being elevated), its interior is quickly exposed for access. In the case of a single-thread or chain-stitch sewing instrument, this case may contain merely a simple looper, as used in single-thread sewing machines, but for lock-stitch or double-thread sewing it houses a looper in the form of a shuttle

31 containing a bobbin 32. The shuttle, as shown, is the ordinary oscillating type which is a conventional article, well understood, and does not require to be described except to say that in the present case, it is oscillated by a cord-operated drum 33 instead of by the usual shuttle holder. This drum is rotated on a stud 34 fixed in the bottom of the case, by the pull of a cord 35, and is returned after being so rotated, by the action of a helical spring contained within it. The cord 35 is pulled out by one arm, 36, of a bell crank lever of which the other arm, 37, is operated by a lost motion link 38 from the shuttle actuator stud 16, already mentioned.

It will be understood that the needle is caused to pierce the fabric on the work-table 27, by the closing of the handgrips, and that when it has entered the shuttle case and started to withdraw on its reverse or upstroke, a loop is formed in the then untensioned thread, at the side of the needle. The looper point 39 of the oscillating shuttle picks into this loop and draws it around the shuttle and around the bobbin 32 therein and therefore around the thread extending from the bobbin, this being also the conventional action of lock-stitch sewing mechanism in the formation of a stitch. In the case of a single-thread instrument a looper without any bobbin is similarly operated by the cord-pulled, spring-returned drum 33 to form a chain-stitch of the single thread. In any case the lost motion represented by the slotted link 38 results in the proper timing of the looper so that it picks up the loop on the return motion produced by the action of the spring. The particular means of actuating the drum or the cord, with the required lost motion, is obviously capable of mechanical variation from that shown but is preferably located on the side of the table base as indicated.

The instrument is used by inserting the work-table under the goods to be sewed and so as to enter the latter under a spring-type pressure foot 40. This comprises essentially a flat spring finger depending from the end of a small shelf 41 projecting from the base part 5 over the work-table, and its only function is to hold the fabric in continuous contact with the table and against being lifted by the needle or by the fabric feed. Its pressure is adjustable by means of the screw and slot 42 by which it is attached to the shelf.

While the length of stitch can be easily controlled by the rate at which the instrument is manually advanced relatively to the goods, the instrument includes an automatic feed mechanism operated by the relative movement of the needle bar and table members. As shown, more particularly in Figs. 10 and 11 but without limitation to the design there shown, the feed includes a claw foot 43 with a serrated bottom to engage the goods. It is pivoted at 44 to the lower end of a link 45 swinging from a fixed pivot 46 on the shelf 41 and has a rear upstanding crank arm 48 which is pivoted to and supports the feed lever 49. The fulcrum of this lever is a sliding fulcrum constituted by a pivot 50 laterally projecting from a vertical slide 51, which is adapted to be raised or lowered by the adjustment of the screw 52 engaging a notch in the slide, by its flat head, as indicated in Fig. 11. The feed lever 49 is slotted to engage the pivot 50 and its upper end is engaged in a cam groove in the actuator 44 on the needle bar 4, already referred to.

When the needle bar descends, the cam groove swings the feed lever 49 in the direction to push the feed claw forward, or to the left in Fig. 10, at

the same time pressing it downwardly upon the goods, so that it pushes the goods along the distance of one stitch. When the bar rises, the lower end of the feed lever swings in the opposite or backwards direction. It first lifts the claw about its pivot 44 and then encounters a lug 51a on the supporting link 45, thus disengaging it from the goods. Thereupon it swings the lifted claw and the link together to the limit of its rearward motion, whereupon it repeats the cycle to make the next feeding stroke. Changing the elevation of the fulcrum 50 relative to the feed lever 49 obviously changes the length of the stroke and hence varies the length of the stitch produced.

From the foregoing description it will be apparent that by simply using the handgrips in a normal manner goods can be sewed with uniform stitching and in situations where the toughness 20 of the goods or their location, or some other considerations, would make impractical the use of a hand-held needle or a stationary machine. The instrument is readily replenished with thread. This is done by swinging the looper case from under the work-table, thus exposing the shuttle, and then removing the bobbin from the shuttle and substituting another in its place and of course also by opening the spool chamber and substituting a new spool for the empty one. The shifting of the looper case is done without rearranging the looper drive because of the flexible looper-operating connection represented in this exemplification by the looper cord.

We claim:

35 1. A hand sewing instrument comprising a pair of crossing handgrip levers fulcrumed to each other at their crossing point, needle bar and base members respectively pivotally supported on said handgrip levers each on pivots in front of, and 40 in rear of, the fulcrum whereby said members have a straight path approach to each other, a straight needle fixed to said needle bar, an oscillating looper mounted on said table member to cooperate with the needle to form a stitch, and 45 means for oscillating said looper comprising a rotary drum, a spring contained within the drum for rotating the looper in one direction of oscillation and a connection between a handgrip lever and said drum for rotating it in the opposite direction.

2. A hand sewing instrument comprising a pair of crossing handgrip levers fulcrumed to each other at their crossing point, needle bar and table members respectively pivotally supported on said handgrip levers each on pivots in front of, and 55 in rear of, the fulcrum whereby said members approach each other in a straight path, a straight needle fixed to said needle bar, a looper mounted in said table member to cooperate with the needle, and means for oscillating said looper comprising a drum member, an operating connection whereby closing movement of the levers rotates the drum in one direction and a spring contained within the drum for oppositely rotating 60 the drum during the opening movement of said levers.

3. A hand sewing instrument comprising a pair of crossing handgrip levers fulcrumed to each other at their crossing point, needle bar and 70 table members respectively pivotally supported on said handgrip levers each on pivots in front, and in rear of, the fulcrum whereby said members approach each other in a straight path, a straight needle fixed to said needle bar, a looper 75 in said table member, a rotary drum for operat-

ing said looper, a cord for operating said drum in one direction, a spring for operating it in the other direction and an operating connection between said cord and one of said handgrips.

4. A hand sewing instrument comprising a pair of crossing handgrip levers fulcrumed to each other at their crossing point, needle bar and table members respectively pivotally supported thereon each on pivots in front of, and in rear of, the fulcrum whereby said members approach each other in a straight path, one of said handgrip levers being hollow and forming a spool chamber and provided with a removable closure for such chamber to confine a spool therein, a straight needle fixed on the needle bar and receiving thread from said spool and a looper in the table member operated by relative movement of said handgrip levers.

5. A hand sewing instrument comprising a pair of cross handgrip levers fulcrumed to each other at their crossing point, needle bar and table members respectively pivotally supported on such levers each on pivots in front of, and in rear of, the fulcrum thereof whereby said members have a straight path of approach, one of said handgrip levers being hollow and constituting a spool chamber, a closure removably applied to said lever to confine a spool in said chamber, a straight needle fixed on the needle bar and receiving thread from said spool and an oscillating looper in the base member operated by the relative movement of said handgrip levers to form a stitch.

6. A hand sewing instrument comprising a pair of crossing handgrip levers fulcrumed to each other at their crossing point, needle bar and table members respectively pivotally supported on said handgrip levers each on pivots in front of, and in rear of, the fulcrum whereby said members approach each other in a straight path, and a straight needle fixed to said needle bar, said table member including a table proper and a looper case movably mounted thereunder, an oscillating looper mounted in said movable case to cooperate with said needle when the case occupies its normal position, and a flexible operating connection between said looper and one of said handgrip levers.

7. A hand sewing instrument comprising a pair of crossing handgrip levers fulcrumed to each other at their crossing point, needle bar and table members respectively pivotally supported on said handgrip levers each on pivots in front of, and in rear of, the fulcrum whereby said members have a straight path approach, said table member including a work-supporting plate and a cup-shaped looper case normally covered thereby, means for mounting said case so that it can be moved to an uncovered position with respect to said plate, a looper mounted in said case, a flexible operating connection between said looper and one of the handgrips and a straight needle fixed on the needle bar to cooperate with said looper to form a stitch.

8. A hand sewing instrument comprising a pair of crossing handgrip squeeze levers fulcrumed at their crossing point, needle bar and work table base members respectively pivotally supported on said handgrips each on pivots in front of, and in rear of, the fulcrum thereby providing parallel motion connections between both said handgrip levers and each of said members maintaining said members in parallelism as they are moved toward and from each other in a straight path approach, a straight needle fixed on the bar member, means on one of the handgrips adapted to confine a spool for supplying the needle with thread, and an oscillating shuttle carried in the work-table base member and containing a bobbin to form a lock-stitch with the thread from said spool.

9. A hand sewing instrument comprising a pair of crossing handgrip levers fulcrumed to each other at their crossing point, needle bar and table members respectively pivotally supported thereon each on pivots in front of, and in rear of, the fulcrum whereby said members approach each other in a straight path, one of said handgrip levers being hollow and forming a spool chamber and provided with a removable closure for such chamber to confine a spool therein and with a shield overlying the handgrip and the thread path, a straight needle fixed on the needle bar and receiving thread from said spool and a looper in the table member operated by relative movement of said handgrip levers.

10. A hand sewing instrument comprising a pair of crossing handgrip squeeze levers fulcrumed at their crossing point, needle bar and work-table members respectively pivotally supported on said handgrips each on pivots in front of, and in rear of, the fulcrum thereby providing parallel motion connections between both said handgrip levers and each of said members maintaining said members in parallelism as they are moved toward and from each other in a straight path approach, the handgrips housing springs fastened thereto and to the respective members to return them to open position, a straight needle on the bar aligned with such approach, means for conducting thread to the needle and a looper carried in the table member for cooperating with said needle to form a stitch.
